United States Patent Office

Des. 181,750
Patented Dec. 17, 1957

181,750

EYE SHIELD

Don A. Reed, Fort Madison, Iowa

Application December 9, 1955, Serial No. 39,266

Term of patent 14 years

(Cl. D57—1)

FIG. 1.

FIG. 2.

I claim:

The ornamental design for an eye shield, substantially as shown.
